UNITED STATES PATENT OFFICE.

HERBERT L. DAY AND ARTHUR L. DAY, OF BANGOR, MAINE.

COMBINATION COUCH-HAMMOCK.

1,177,687.

Specification of Letters Patent.

Patented Apr. 4, 1916.

Application filed March 11, 1915. Serial No. 13,574.

To all whom it may concern:

Be it known that we, HERBERT L. DAY and ARTHUR L. DAY, citizens of the United States, residing at Bangor, in the county of 5 Penobscot and State of Maine, have invented certain new and useful Improvements in Combination Couch-Hammocks, of which the following is a specification.

Our invention consists of an improved 10 combination couch-hammock, and is fully illustrated in the accompanying drawing which is an oblique projection of the device, with covering removed, and one side-arm broken away.

15 Similar letters refer to corresponding parts throughout the drawing.

The object of our invention is to provide a couch-hammock having a yielding back adapted to conform to the human figure and 20 to be capable of assuming different inclinations with reference to the seat, even to the horizontal or nearly so, thus, when desired forming a couch.

We provide a foundation or bed-frame, 25 A, preferably rectangular as commonly, and a specifically constructed back-frame B, hinged to the bed-frame or to posts a a, rising from the back corners of the bed-frame. Each of the side-members b b, of the back 30 is formed preferably with a reverse curve b' for the purpose hereinafter described and the top and bottom members of the back preferably with a backwardly projecting curve b''. A spring-sheet C, to occupy 35 wholly or partly the space between the four members of the frame is rigidly secured to the side-members b b, but preferably not to the top or bottom members. A longitudinally adjustable connection D, of any usual 40 or convenient form between the side-members b b, of the back and the side arms E, of the hammock holds the hinged back at any convenient inclination.

We further provide a foot-rest F, adjust-

able longitudinally to accommodate persons 45 of different heights by means of teeth f, on its side-members adapted to engage with eyes or slots c c, on the front or side-members of the bed-frame, and having a foot-board f' adapted for partial rotation upon 50 the front-member of the rest F, the amount of rotation being regulated by stops f'' f''.

The object of the reverse curve on the side-members of the back is to permit the 55 spring to conform to the figure and fill and support the curves of the back, while the outward curve of the upper member is to allow backward extension of the spring without bringing the head or body in contact with the rigid upper-member.

Both seat and back are cushioned and when the back is dropped approximately to the horizontal position the device becomes 60 essentially an inclined couch.

Having thus described our invention, we 65 claim and desire to secure by Letters Patent:

1. In a couch hammock the combination of a bed frame, a back hinged to said frame and having each of its side members formed 70 with a reverse curve, and its top and bottom members with a backwardly projecting curve, and adjustable connections for the upper part of the back; substantially as described.

2. In a couch hammock the combination of a bed frame, a back hinged to said frame, and having each of its side members formed with a reverse curve, and its top and bottom 80 members with a backwardly projecting curve, a spring sheet rigidly secured to said side members, and adjustable connections for the upper part of the back.

HERBERT L. DAY.
ARTHUR L. DAY.
